UNITED STATES PATENT OFFICE.

MAX KLINE, OF NEW YORK, N. Y.

VANITY CASE.

Application filed March 22, 1924. Serial No. 701,144.

To all whom it may concern:

Be it known that I, MAX KLINE, a citizen of the United States, and a resident of the city of New York, borough of the Bronx, 5 in the county of Bronx and State of New York, have invented a new and Improved Vanity Case, of which the following is a full, clear, and exact description.

This invention relates to containers and 10 has particular reference to an improvement in vanity cases of the type which are employed as a combined container for rouge and face powder compacts.

One of the outstanding objects of the 15 present invention resides in the provision of means for separately holding the several compacts within the case whereby upon swinging of the cover thereof to open position the compact holding means may be 20 relatively separated whereby access may be simultaneously gained to both compacts.

The present invention pertains particularly to a compact carrier which is adapted 25 to be located within the standard forms of containers or box which include a body and cover and in which the carrier is composed of a stationary member anchored within the bottom of the box and a movable member having slideable and hinged connection with 30 the stationary member whereby when the cover of the container is opened the movable member is moved to a position to uncover the stationary member.

As a further object the invention comprehends a compact carrier which is comparatively simple in its construction, inexpensive to manufacture and produce and which is capable of ready assembly with the 35 standard forms of boxes or cases.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

In the drawings—

Figure 1 is a plan view of a vanity case constructed in accordance with the invention and illustrating the same in opened condition.

Fig. 2 is a longitudinal sectional view

therethrough, taken approximately on the line indicated at 2—2 of Fig. 1.

Fig. 3 is a similar view illustrating the carrier case in closed condition.

Fig. 4 is a transverse sectional view taken approximately on the line indicated at 4—4 of Fig. 3.

Fig. 5 is a perspective view of the stationary carrier member with the movable member removed therefrom.

Referring to the drawings by characters of reference, 10 designates the body and 11 the cover of a standard form of vanity case or container in which the cover is hinged as 15 at 12 to the body and is provided with a mirror 13.

The carrier constituting the invention consists of a stationary member 14 and a 20 movable member 15 which are of substantially the same configuration as the container body. The member 14 is provided with peripheral depending and upstanding lugs 16 and 17, the former being designed 25 to rest on the bottom of the body 10 for spacing the same from the bottom and the latter being designed to snap under the internal annular shoulder 18 formed by the restricted upper end 19 of the body over 30 which the cover 11 telescopically fits when in closed position.

The member 14 is provided with an opening 20 from which a depending flange 21 projects into engagement with the bottom of the body and which flange defines a compartment for receiving 35 the rouge compact R and puff or applicator A. The opening 20 and compartment for the rouge compact is preferably eccentric and located adjacent what will be termed the rear portion of the member 14 and the 40 said member is formed at this point with a peripheral bearing knuckle 22 which receives the bight 23 of a yoke, the side arms 24 of which are provided at their free ends with inwardly extending terminals 25. The 45 movable member 15 which is in the nature of a tray defines a compartment within which the powder receptacle P and puff or applicator B is received. The under side or 50 bottom wall of the member 15 has secured thereto in transversely spaced relation bearing sleeves 26 which are designed to receive the side arms 24 of the yoke whereby the movable member 15 is swingingly and 55 slidably associated with the stationary member 14. Preferably the member 14 is formed 60 with depressions 27 in its upper face for

receiving and accommodating the yoke and bearing sleeves 26 when the members 14 and 15 are in nested superposed relation.

After the carrier is associated or assembled with the container body 10 as illustrated, it is obvious that when the members 14 and 15 are nested in superposed relation as illustrated in Figs. 3 and 4 that the said carrier compacts and applicators lie wholly within the confines of the container body 10 so that the member 14 and its contents are covered and concealed by the member 15 and its contents, thus admitting of the closing of the cover 11 of the case. When the cover 11 is opened and it is desired to gain access to both compacts simultaneously, the manipulating lip 28 formed at the forward upper part of the movable member 15 is employed to slightly swing the member 15 and yoke upwardly at an angle, after which the said member 15 is moved forwardly due to the slidable connection until the sleeves 26 engage the inturned terminals 25 of the arms 24 which constitute stops for limiting said sliding movement. When the member 15 is moved outwardly to the limit of its movement it will be seen that the compartment for the rouge compact is exposed so that the user may gain access thereto. In this position the bottom of the member 15 rests on the upper edge of the flange or side wall of the body 10 and the user may readily hold the complete device in the palm of the hand. To return the parts to normal position, the member 15 is slid inwardly until it registers with the interior of the body 10, at which time it may be swung downwardly to overlie the member 14 and permit of the closing of the cover 11.

I claim:

1. In a vanity case including a body and cover, a stationary compact carrier member secured within the bottom portion of the body, a movable compact carrier member, a means of connection therebetween to permit of relative swinging movement of the movable member to a projected position

above the upper open end of the body and sliding movement to uncover the stationary member whereby access may be gained to both of the compacts, the said means of connection consisting of a yoke swingingly connected to the stationary member, and a slid-
able connection between the yoke and the movable member.

2. In a vanity case including a body and cover, a stationary compact carrier member secured within the bottom portion of the body, a movable compact carrier member, a means of connection therebetween to permit of relative swinging movement of the movable member to a projected position above the upper open end of the body and sliding movement to uncover the stationary member whereby access may be gained to both of the compacts, the said means of connection consisting of a yoke swingingly connected to the stationary member, a slid-
able connection between the yoke and the movable member, and means on the yoke for limiting the sliding movement of the movable member in a direction to uncover the stationary member.

3. A twin compact vanity case comprising a body and a cover, a compact carrier including a stationary member secured within the bottom portion of the body having an eccentric opening provided with a depending flange defining together with the bottom of the body a receptacle for one of the compacts and its applicator element, a substantially U-shaped yoke having hinged connection with the stationary member at one edge thereof and having the side arms straddling the lower compact receiving compartment, a movable member defining an upper compact and applicator receptacle having bearing sleeves on its under side slidably engaging the arms of the yokes, and in-turned outer terminals on said arms for engaging the bearing sleeves to limit the outward sliding movement of the upper receptacle.

MAX KLINE.
